US0D1088686S

(12) **United States Design Patent** (10) Patent No.: **US D1,088,686 S**
(45) Date of Patent: ** Aug. 19, 2025

(54) **COFFEE MACHINE**

(71) Applicant: **BSH Hausgeräte GmbH**, Munich (DE)

(72) Inventors: **Alexander Stuhler**, Munich (DE);
Sören Strayle, Munich (DE); **Janina Forberger**, Munich (DE)

(73) Assignee: **BSH Hausgeräte GmbH**, Munich (DE)

(**) Term: **15 Years**

(21) Appl. No.: **35/521,626**

(22) Filed: **Mar. 13, 2024**

(80) **Hague Agreement Data**

Int. Filing Date: **Mar. 13, 2024**

Int. Reg. No.: **DM/238170**

Int. Reg. Date: **Mar. 13, 2024**

Int. Reg. Pub. Date: **Jul. 12, 2024**

(57) **CLAIM**

The ornamental design for a coffee machine as shown and described.

DESCRIPTION

1. Coffee machine

1.1 : Perspective

1.2 : Left

1.3 : Front

1.4 : Right

1.5 : Top

1. Title of the product incorporating the design: coffee machine; 2. Use of the product incorporating the design: use as a coffee machine; 3. Essential features of the design: as shown by the shapes of design 1; 4. Photograph designated to best show the essential features of the design: perspective view of design 1. 5. Basic Design: design 1.

1 Claim, 5 Drawing Sheets
